Attys.

UNITED STATES PATENT OFFICE.

HENRY E. BRYANT, OF PROVIDENCE, RHODE ISLAND, ASSIGNOR TO TUBULAR WOVEN FABRIC COMPANY, OF PAWTUCKET, RHODE ISLAND, A CORPORATION OF RHODE ISLAND.

SPOOL OR REEL.

Original application filed August 6, 1923, Serial No. 655,945. Divided and this application filed October 16, 1925. Serial No. 62,760.

The present invention relates to an article or structure in the nature of a spool or reel adapted to carry a supply of material such as may be generically designated as slender 5 elongated material, and may be specifically strip or ribbon stock, cord, wire, rope, tubing, or the like, wound in the form of a coil, and to be mounted rotatably in a manner permitting such strip or analogous mate- 10 rial to be drawn off for use. More particu- larly, the embodiment of the present in- vention herein illustrated has been designed and intended for application and use with a machine for winding or coiling soft iron 15 strip material into a helix so as to form a flexible tube or sheathing, such a machine being illustrated in my application for Let- ters Patent of the United States, filed Au- 20 gust 6, 1923, Serial No. 655,945, entitled "Machine for making cable armor and flex- ible metallic conduit"; and the present appli- cation is a division of that above identified.

As provided for the special uses of said machine, the spool or reel herein described 25 is designed and adapted to receive a ready wound coil of strip or ribbon stock, of the sort used in making the well known flexible metallic conduit for electrical and other pur- 30 poses, or flexible metallic armor upon elec- trical cables, and analogous goods; receiv- 35 ing the coils of such stock in the condition in which they are furnished by the makers, without need of rewinding, and holding the coils in a condition and position such that 40 the stock may be drawn off from the outer circumference of the coil placed on the spool. This specific embodiment of the invention is 45 illustrative, however, and not limitative as to the forms and dimensions in which the 50 principles of the invention may be embodied, or the uses or purposes to which it may be put, or the characteristics of the material which may be placed upon the spool embodying such principles.

45 In the drawings,—

Fig. 1 is an axial section of the illustra- 55 tive embodiment of the invention above referred to, showing the same in association with a supporting means and with means for guiding to a place of use the material held by the spool;

Fig. 2 is an elevation as seen from the

right hand side of Fig. 1, with the supporting means shown in section;

Fig. 3 is an elevation, partly broken away, 55 of the detachable head or retainer which forms a part of the complete spool;

Fig. 4 is a detail view showing in perspective one of the eccentric load centering and locking elements with which the spool is 60 provided.

Describing now the spool or reel here shown for illustration, said spool comprises as its principal parts an end of head mem- 65 ber 11, an opposite end or head member, or retainer, 12, and a hub or disc member 13, to which said removable head or retainer 12 is detachably connected. The disc or hub 13 is secured to the head 11, and spaced apart therefrom, by bolts 14, having threaded ends 70 screwed into tapped holes in the hub 13 and shoulders 15, limiting the penetration of such threaded ends. The head ends of the bolts 14 are set in the head or end member 75 11 of the spool, and may be threaded or otherwise secured therein so as to prevent relative endwise movement. In the form here shown, however, such endwise move- 80 ment in the direction which would narrow the space between the parts 11 and 13 is pre- 85 vented by accessory parts later described.

Shafts or rods 16, supporting and center- 90 ing the load on the spool, are mounted in the head 11 and hub 13, passing through bearing apertures in the former and being seated in recesses provided for their recep- 95 tion in the periphery of the latter. Those parts of said shafts or rods which cross the space between the head 11 and hub 13 are enlarged and made eccentric to the trun- nions or supporting parts of the shafts which have their bearings in the head and hub, as above described. The ends 17 of the shafts project outwardly from the hub far enough to pass through and project be- 100 yond the detachable head or retainer 12, and are threaded to receive clamp nuts or abut- ments 18.

The detachable head or retainer has a central hole 19 adapted to fit over a boss 20 centrally arranged on the outer side of the hub 13. Said retainer is also provided with hooks 21 and notches 22 adapted to embrace and receive, respectively, the protruding

ends 17 of the centering shafts. This construction enables the detachable head to be engaged with, or disengaged from the main portion of the spool by giving it a partial rotation, without wholly removing the clamping nuts; but such nuts when tightened up on the retainer, prevent removal thereof.

Either or both heads may be made as discs, 10 or of skeleton form, as here shown, with a central part, arms and a rim; or as a spider with a central part and arms only.

23 represents a support or bearing of any suitable character, or a spindle or shaft on 15 which the spool may be mounted. That here shown is a stationary bearing sleeve about which the spool may rotate. On this support are a fixed rib 24, and a removable collar 25, the latter secured by a set screw 26, 20 and the head 11 is confined between such rib and collar with sufficient freedom for rotation. There is also mounted on the support 13 and close to the outer side of the head 11, a gear 27 which is confined rotatably between the same rib 24 and a collar 28 secured by a set screw 29. The gear 27 serves in this construction as one embodiment of the means, previously referred to, which prevents endwise movement of the bolts 14 30 relative to the head 11, in a direction which would permit the hub 13 to approach the head. The centering shafts are also means for securing the same result, inasmuch as their enlarged eccentric central portions provide shoulders abutting against the inner surfaces of the head 11 and hub 13 so as to prevent approach of one to the other.

The gear 27 has an additional function, 40 namely, to transmit rotary movement from one of the centering shafts to all the others. Said shafts are spaced equally from and around the axis of the spool and carry pinions 30 meshing with the gear 27, and one of them has a squared end 31 adapted to receive a wrench. They are keyed or otherwise rigidly secured to their respective pinions so that relative rotation between them and their pinions is impossible. All of the pinions have the same pitch diameter. 45 Hence when the shaft equipped with the squared end is rotated, the other centering shafts are equally rotated in the same direction. They are all initially set up with their eccentric portions bearing the same relation 50 to the spool as a whole, so that when the eccentric part of one is turned inward or outward, the others are turned in the same manner and to the same degree; that is, the eccentrics are all turned inward with respect to the axis of the spool, or all turned outward at the same time. A lock 32, which, 55 as here shown, is a latch mounted on the head 11, but may be of other suitable character, is arranged to engage one of the pinions 30 detachably so as to retain the eccen-

tric shafts in any position in which they may be put. The same or an equivalent lock may be applied to the gear 27.

33 represents a guide arm having a roll 34 at its ends, around which the strip passes from the spool on its way to the winding point. The guide arm here shown is a part of the machine disclosed in my parent application before identified, and is pivoted at 35 on a collar 36 fixed to a tubular spindle 37, which rotates within the bearing 23. The strip passes around the guide roll 34 and a second guide roll 38, mounted on the collar 36, and thence through the bore of 75 the tubular shaft to the winding instrumentalities. A cable 39 to be armored may also be passed through the shaft. The guide arm may be held in normal position beside the spool by means of a bracket 40 on the collar 36, and a branch 41 from the arm 33, 80 said bracket and branch being coupled together by a removable pin 42.

In replenishing the spool, the guide arm is released by withdrawing the coupling pin 90 42 and is then turned down into the dotted line position 33^a, where it is near enough to the axis of the spool to permit withdrawal of the retainer 12; for the distance between the pivot 32 and the opposite side of the 95 collar 36 is less than the diameter of the hole 19 in the retainer. The clamp nuts 18 are backed off enough to free the retainer, and the latter is turned far enough to release its hooks from the clamp nuts, and is 100 moved away from the main body of the spool in a manner represented by the dotted line construction 12^a.

If at the time of replenishment, there is a cable in place passing through the spool and 105 through a reserve coil of the strip material, it is necessary to remove the retainer side-wise from the cable to put it out of the way of the reserve coil, and in order thus to disengage it from the cable, the retainer is provided with gateways 43 and 44 in its central portion and rim respectively, wide enough 110 to permit passage of the cable. A gate 45 is arranged to be secured across the gateway 43 with provision for being turned aside to open such gateway. This gate, while a useful adjunct, is not an essential feature of the spool.

With the removal of the retainer as just described, a coil of the material may be 120 passed over the hub 13 and the centering shafts 16, the latter having been turned so that their eccentric parts project inwardly, and then the coil is centered and made fast to the spool by turning the shafts so that their eccentric parts project outwardly. Then the retainer or detachable head is 125 replaced by reversal of the steps employed in removing it.

In here describing the environment and 130 mode of use of my improved spool according

to the disclosure of my parent application, I have intended merely to explain the utility of the invention with reference to an illustrative use, and not to limit the invention 5 and my protection to that specific use. The device here illustrated is one embodiment of a generic invention in a spool or reel adapted to receive material of elongated and narrow form, whether the same is ribbon stock, wire, 10 rope, tubing, or anything of that nature, which has been previously formed into a coil; thus avoiding the loss of time and expense of rewinding the material on the spool prior to use, as well as the expense of providing a spool with each coil.

What I claim and desire to secure by Letters Patent is:

1. A spool for holding strip material, said spool having a detachable head, and centering means adapted to occupy the interior of such roll, said centering means comprising rotatable shafts having eccentric portions adjacent to the inner circumference of such roll and being so rotatable as to apply outward 25 pressure to the roll.

2. A spool or reel for holding slender, elongated material and comprising a central structure including shafts equally spaced about and parallel with a common axis, said 30 shafts being rotatably mounted in said central structure and having eccentric portions arranged to be brought by such rotation into position more or less distant from said axis.

3. A reel or spool comprising a head, a central structure adapted to receive a surrounding coil of previously coiled elongated,

slender material, and centering means associated with said central structure and having eccentric portions movable inwardly and 40 outwardly with respect to the axis of the spool.

4. A spool comprising a head, a hub or disc member axially displaced from the head, a second head detachably connected with said hub, and centering shafts rotatably mounted in the first named head and said hub, and having eccentric portions adapted to be turned inwardly or outwardly with respect to the axis of the spool.

5. A spool comprising a head, a hub or disc member axially displaced from the head, a second head detachably connected with said hub, centering shafts rotatably mounted in the first named head and said hub and having eccentric portions adapted to be turned inwardly or outwardly with respect to the axis of the spool, pinions mounted on said shafts, and a common transmission gear concentric with the spool and meshing with all of said pinions for transmitting rotation from one to another thereof.

6. A spool comprising a central structure adapted to enter the interior of such a roll, a head adapted to engage one end of the roll, 65 a detachable head adapted to engage the opposite end of the roll, and means for securing said detachable head to the central structure, the detachable head having a central opening and a lateral passage from said opening to 70 the periphery of the head.

In testimony whereof I have affixed my signature.

HENRY E. BRYANT.
